(57) **CLAIM**

The ornamental design for a display screen with icon, as shown and described.

DESCRIPTION

The design patent application file contains at least one drawing executed in color. Copies of this design patent application publication with color drawing(s) will be provided by the Office upon request and payment of the necessary fee,

FIG. 1 is a front view of a display screen with icon showing our new design;

FIG. 2 is a front view of the icon shown in FIG. 1;

FIG. 3 is a front view of a second embodiment of the design shown in FIG. 1;

FIG. 4 is a front view of the icon shown in FIG. 3;

FIG. 5 is a front view of a third embodiment of the design shown in FIG. 1; and,

FIG. 6 is a front view of the icon shown in FIG. 5.

The evenly spaced broken lines illustrate a display screen. The dot-dash broken line illustrates a boundary of the claim. None of the broken lines form part of the claimed design.

1 Claim, 6 Drawing Sheets
(4 of 6 Drawing Sheet(s) Filed in Color)
